United States Patent Office.

JOHN AUGUSTUS LYNCH, OF BOSTON, MASSACHUSETTS.

Design No. 4,653, dated February 14, 1871.

DESIGN FOR AN ENGINE-GOVERNOR CASE.

The Schedule referred to in these Letters Patent and making part of the same.

To all persons to whom these presents may come:

Be it known that I, JOHN AUGUSTUS LYNCH, of Boston, in the county of Suffolk and State of Massachusetts, have invented or produced a new, useful, and ornamental Design for the Case of an Engine-Governor; and do hereby declare such design to be represented in the accompanying drawing, of which.

Figure 1 is a front elevation;

Figure 2, a side view; and

Figure 3, a horizontal section of the case.

The main body A of the case in its general form is what may be termed "acorn-shaped," the dome a and sides being corrugated.

The bottom b of the sides is semispherical, and is connected with a circular base, d, by means of a hollow standard, c, which opens into the case.

A hollow or tubular arm, e, projects from one side of the standard.

The whole may be surmounted by an acorn, f, or other proper finish or ornament, which, however, I do not include in the design.

The several parts in other respects have shapes as indicated in the drawing.

I claim—

The design, substantially as described, for the case of an engine-governor.

JOHN AUGUSTUS LYNCH.
